JOHN FRASER, FRANK FURNESS, AND GEORGE W. HEWITT, OF PHILADELPHIA, PENNSYLVANIA.

Design No. 4,159, dated June 21, 1870.

DESIGN FOR BUILDING-FRONTS.

The Schedule referred to in these Letters Patent and making part of the same

---

We, JOHN FRASER, FRANK FURNESS, and GEORGE W. HEWITT, of the city and county of Philadelphia, and State of Pennsylvania, have invented and produced a new and original Design for a Building Front, of which the following is a specification.

The front of the building is made in the modern Greek style, the base, which is high as the water-table, is dressed rough in rock-work, the basement, as well as the first-story windows, have segmental arch-heads. The windows of the second story are made with semicircular heads.

The cornice is of stone, also the dormers, which have semicircular heads covered by a pointed roof.

The roof is of the Mansard pattern, and is covered with slate, and is surmounted by a light iron rail.

All the keystones of the first, second, and dormer windows are ornamented with incised work.

The door is approached by a double flight of circu-

lar stone steps, and directly over it is a balcony supported by stone brackets, the sides and front of which are ornamented with incised work, and the door is provided with a semicircular arched head, on the keystone of which is cut a lion's head.

A balcony, supported by stone brackets, may be placed on the right or the left-hand side of the building, as may be desired, although the said balcony, whether added or not, will not alter the general design of the front.

We claim as our invention—

The design for a building front, as shown.

JOHN FRASER.

FRANK FURNESS.

GEO. W. HEWITT.
